BUMPER

Charles H. Borten, Moorestown, N. J., and Abram Hart,
Havertown, and Stanley I. Bostick, Ambler, Pa.

Application April 8, 1955, Serial No. 35,427

Term of patent 14 years

(Cl. D14—6)

Fig. 1.

Fig. 2.

Figure 1 is a perspective view of a bumper embodying our new design; and

Figure 2 is another perspective view thereof.

The dominant feature of our design resides in the full line portion of the drawing.

This application is a continuation-in-part of our application for an exhaust pipe grill, filed on March 11, 1955, whose Serial Number is D.35,005.

We claim:

The ornamental design for a bumper, as shown and described.
